(57) **CLAIM**

The ornamental design for a coaxial cable connector, as shown and described.

DESCRIPTION

FIG. 1 is a front perspective view of a coaxial cable connector showing our new design in use condition;

FIG. 2 is a back perspective view thereof;

FIG. 3 is a top plan view thereof, the bottom plan view being a mirror image;

FIG. 4 is a left side elevation view thereof, the right side elevation being a mirror image;

FIG. 5 is a front elevation view thereof;

FIG. 6 is a back elevation view thereof; and,

FIG. 7 is a front perspective view of the coaxial cable connector showing an unclaimed knurl pattern.

The broken line portion of the figure drawings is included for the purpose of illustrating environment and forms no part of the claimed design.
